WEAR GUARD FOR TROUSERS

Irving Pearl, Brooklyn, N. Y.

Application April 28, 1934, Serial No. 722,848

5 Claims. (Cl. 2—232)

This invention is a wear guard for trousers, and is directed more particularly to a relatively small inexpensive device adapted to be associated with the lower marginal portions of trouser legs 5 in such manner as to preclude them from becoming worn or frayed due to contact with the heel portions of the shoes of the wearer.

It is well known that after trousers have been worn for a while the constant rubbing engagement between the interior of the legs at the cuff of the trouser causes the fabric to be worn away at this point with the result that the trousers become worn and frayed in a manner to render them unsightly and to require repair. Repair 10 at this point is generally difficult to carry out without shortening the trouser with attendant unsatisfactory appearance.

The present invention provides a simple and convenient device which will preclude undue wear of trousers from this cause. I am aware 20 that it has heretofore been proposed to provide the interior of trouser cuffs with strips of cloth or tape permanently sewed in position and intended to take the wear incident to rubbing 25 against the shoes and it has also been suggested to utilize metal devices for the same purpose. The metallic devices which have been suggested, however, have been of an unsatisfactory nature 30 for various reasons. For example, one of these prior devices embodied metal plates with wire staples associated therewith, and so constructed that the wire staples could either be bent over or the device secured in place by stitches. Such devices have not proven to be satisfactory for 35 various reasons. They require extraneous means for fastening them into position or the employment of tools to properly bend the staples. They are visible when worn. The stitches wear away quickly and the devices become lost and 40 if the bending of the staples is employed, this operation must be carried on with tools and with considerable skill, so as to leave the points of the staples protected in a manner not to injure the shoes or the wearer. For these reasons and 45 others, the device in question has never been practically accepted for general use.

Another form of device which has been suggested is a two part metallic arrangement requiring expensive dies in the manufacture and 50 also requiring very considerable skill in assembling these parts in a proper relation on a garment, in such manner as to preclude the pulling of the garment out of shape while still providing a proper mounting for the device. A guard of 55 the type of this invention in order to be practical

and acceptable to the trade must be simple and inexpensive and must be so easy to install that even the most inexperienced user can operate it. It must require no extraneous fastening means and its attachment must be readily accomplished by the uninitiated. It must be simple in construction and yet thoroughly efficient in its operation and it must be so constituted that when placed on a pair of trousers it cannot inadvertently become detached and lost.

The object of the present invention is to fulfill all these requirements and in a simple and efficient manner and to produce a device which may be marketed at a low cost to the ultimate consumer.

A further object of the invention is to provide a structure of this character which may be readily changed from one pair of trousers to another in a jiffy and the structure of which will not be weakened by such change.

Speaking generally, the present invention in one of its preferred practical forms comprises a relatively flat body portion, which will herein-after be generically termed, a "wearing plate". Two of these devices are adapted to be associated 25 with each trouser leg with one positioned on each side of the medial line of the back thereof. Along one lateral edge of each wear plate and on the back face thereof is positioned a longitudinally extending tube of oval or elongated 30 cross section and open at its opposite ends. Through this tube extends a wire rod, the opposite ends of which are bent beyond the ends of the tube into parallel relation and sharpened to form attaching prongs. That portion of the 35 wire which is housed within the tube is offset, so that when the prongs are collectively moved, a resilient co-action will result between the rod and the tube so as to normally maintain the rod in one of two predetermined terminal positions 40 which may be either a fully unlocked position or a fully locked position. The prongs may be moved through intermediate positions by the application of manual pressure thereto, but when released will immediately partake 45 of either the fully unlocked or fully locked positions. A plurality of spurs are associated with each wear plate in a manner to lock the wear plate against edgewise movement in a direction to release the plate when the prongs are 50 in locking position.

Among the important features of the present invention are its extreme simplicity in construction, the ease with which it may be attached or detached and its ability to retain its position on 55

the trouser leg against inadvertent attachment.

Features of the invention, other than those adverted to, will be apparent from the hereinafter detailed description and claims, when read in conjunction with the accompanying drawing.

The accompanying drawing illustrates one practical embodiment of the invention, but the construction therein shown is to be understood as illustrative, only, and not as defining the limits 10 of the invention.

Figure 1 is a perspective view of the device of this invention.

Figure 2 is a section on the line 2—2 of Figure 1.

Figures 3, 4 and 5 are pictorial views showing 15 the manner of attachment of the device to a trouser leg.

Referring to the drawing, 1 designates the so-called wear plate. This plate may be conveniently made from sheet metal or it may be 20 formed from other suitable material, such as "Bakelite", celluloid or the like by means of dies or molds. It may be made of resilient material or non-resilient material as will be presently explained. It is preferably made of the 25 shallow shell-like form illustrated and of appreciably greater length and width. Along one of its ends, it is provided with a hollow tubular member 2 slightly shorter than the length of the wear plate. This tubular part is made integral with the wear plate. If the plate is made from metal the part 2 may be struck up from the metal in the form of a tongue which is curled over by means of appropriate dies to constitute the tubular section. If the device is 30 molded or made in dies, this tube 2 may be formed or cast integral with the plate 1.

An important characteristic of the tube 2 is that it is of elongated cross section with its greatest dimension in a direction transversely of 40 the plate 1. As shown, the sides of the tube which are of the greatest width are made substantially parallel to one another and are united by curved ends as shown, so as to give a substantially oval cross section.

45 A wire rod is passed through this tube 2, so that the intermediate portion of the wire is housed within the tube, while the opposite end portions of the wire are bent into parallel relation to one another and in a direction perpendicular 50 to the axis of the tube to form attaching prongs 3, the free ends of which are sharpened as indicated at 4. That portion of the wire which is housed within the tube 2 is so formed that the parts immediately adjacent the prongs are in 55 alinement with one another as indicated at 5, while that portion of the rod which connects the parts 5 to one another is offset on a long sweeping curve as indicated at 6. If the tube 2 is of resilient material, the wire which forms the prongs 60 may be relatively rigid, whereas if the tube 2 is rigid, this wire should be relatively resilient, although both of these parts may be resilient as would be the case if ordinary spring wire were employed within a sheet metal tube 2. In any 65 event, the wire is so formed that the offset 6 lies in the same plane as the prongs 3 and thus the wire element embodying the parts 3, 5 and 6 is adapted for two distinct positions of rest with respect to the tube. These positions of rest are 70 manifestly due to the presence of the offset within the flat tube. The position shown in full lines in Figures 1 and 2 and in Figure 3 is the unlocked position.

The wire part may, however, be swung over 75 into the dotted line position of Figures 1 and 2

by applying sufficient force to the prongs or to the plate 1 to overcome the inherent resiliency of the parts and cause the offset 6 to be readily compressed sufficiently to permit rotary movement of the prongs with respect to the plate. When the prongs have been moved to the position indicated in dotted lines in Figures 1 and 2, the offset will hold the prongs in this position which constitutes the fully locked position.

The plate is provided with a plurality of 10 sharpened spurs 7 which are bent back in the direction of the tube 2 and with additional sharpened spurs 8 carried by projecting arms 9 which extend beyond the ends of the plate. The spurs 7 preclude edgewise shifting of the plate in the 15 direction of the tube 2, which would serve to release the device from a garment, while the spurs 8 preclude longitudinal edgewise shifting of the device which might place a bending strain upon the prongs.

20 The manner of employing the device is graphically shown in Figures 3, 4 and 5. Four of these devices are used in connection with each pair of trousers, two being associated with each trouser leg. One is positioned on each side of the crease 25 at the back of the leg and at the interior of the leg so as to underlie the cuff of the trouser. All of these devices are attached in the same way and in Figures 3-5, I have shown the manner of attaching one of them. To install the device 30 the prongs are moved to the fully unlocked position indicated in full lines in Figure 1. This having been done, the prongs are pressed into the fabric as shown in Figure 3. After the prongs have been fully impaled, the wear plate is folded over, 35 as indicated in Figure 4, through the application of sufficient manual force to flex the resilient wire or tubular parts.

40 Figure 4 shows the plate folded substantially half way. As the folding of the plate is completed to the position of Figure 5 which shows its complete attachment, the spurs 7 and 8 impale the fabric and lock the device in position. It is worthy of note that after the device has been folded to substantially the position shown in Figure 4, 45 with the offset 6 of the wire slightly beyond dead center the inherent resiliency of the parts will complete the folding operation. In other words, the parts will snap into locked position, so that the spurs will be automatically forced into the fabric, 50 this being particularly so because the prongs when in fully locked position are below the points of the spurs as shown in Figures 1 and 2.

55 In practice, the quick snapping of the parts into locked position efficiently forces the spurs into the fabric, so that a strong and efficient gripping is obtained. When the device is in fully locked position, it is locked against movement in every direction, so that it cannot possibly fall off or become inadvertently displaced. However, if at any time it is desired to remove the devices for use on any pair of trousers, this can be readily accomplished by simply reversing the 60 operation stated and which operations do not in anywise detrimentally affect the adaptability 65 of the device for repeated use. No tools are required for the attachment and detachment of the device and no extraneous attaching means is employed. The device is on the contrary a self contained resilient clip, the resiliency of 70 which maintains the parts in a position, so that they may be easily attached to a garment and resiliently locked in position thereon. I have found that four of these devices can be more rapidly attached to a pair of trousers in less 75

time than it is possible to sew on a single tape. Furthermore, the use of these devices at either side of the crease appreciably prolongs the crease at this point for the shoe does not engage with the trousers adjacent the crease and tend to iron out the crease, but, on the contrary, the shoes engage with the plates 2, while the trousers at the lower edge do not engage with the back of the shoes and thus are free from wear by friction at these points.

If the devices are worn at the very lower edge of the cuff, they will prevent contact between the trouser and the pavement and thus preclude wear from this source. Furthermore, they space the trousers from the shoe at all times and keep the trousers clean.

Having thus fully described the invention, what I claim as new and desire to secure by Letters Patent is:

1. A wear guard for trousers comprising a wear plate provided on the back thereof and adjacent one edge with a tubular member extending longitudinally of the plate, said tubular member having a cross section of greater interior dimension in the direction of the width of the plate than in the direction of the thickness of the plate, a wire extending through said tubular member with the opposite ends of the wire projecting beyond the opposite ends of the tubular member, that portion of the wire within the tubular member being offset in a radial direction and the projected ends of the wire being bent into parallel relation in the plane of the offset to form attaching prongs, and pointed spurs mounted on said plate and projecting in a rearward direction to impale the fabric of the trousers when the plate is moved into face abutting relation thereto with the prongs impaled in said fabric.

2. A wear guard for trousers comprising a wear plate provided on the back thereof and adjacent one edge with a tubular member extending longitudinally of the plate, and of less width than the length of the plate, said tubular member having a cross section of greater interior dimension in the direction of the width of the plate than in the direction of the thickness of the plate, a wire extending through said tubular member with the opposite ends of the wire projecting beyond the opposite ends of the tubular member, that portion of the wire within the tubular member being offset in a radial direction and the projected ends of the wire being bent into parallel relation in the plane of the offset to form attaching prongs, and pointed spurs mounted on said plate and projecting in a rearward direction to impale the fabric of the trousers when the plate is moved into face abutting relation thereto with the prongs impaled in said fabric.

3. A wear guard for trousers comprising a wear plate provided on the back thereof and ad-

jacent one edge with a tubular member extending longitudinally of the plate, and of less width than the length of the plate, said tubular member having a cross section of greater interior dimension in the direction of the thickness of the plate, a wire extending through said tubular member with the opposite ends of the wire projecting beyond the opposite ends of the tubular member, that portion of the wire within the tubular member being offset in a radial direction and the projected ends of the wire being bent into parallel relation in the plane of the offset to form attaching prongs, and pointed spurs mounted on said plate and projecting in a rearward direction to impale the fabric of the trousers when the plate is moved into face abutting relation thereto with the prongs impaled in said fabric, certain of said spurs being inclined in the direction of the tubular member to preclude inadvertent withdrawal of the prongs from the fabric and certain other of said spurs extending in a direction perpendicular to the plane of the plate to preclude edgewise movement of the plate in a longitudinal direction.

4. A wear guard for trousers comprising a wear plate, a substantially U-shaped resilient attaching member, the legs of which are pointed and are parallel to one another, the parts adjacent the legs being in line with one another and perpendicular to the legs and the part which connects the aligned parts being radially offset in the plane of the legs, bearings formed on the plate and engaging with the aligned parts of the U-shaped member to mount the U-shaped member on the plate with the offset part of the U-shaped member in camming relation to the plate to permit the prongs to be resiliently maintained in locking position with respect to the plate, and spurs formed on the plate to impale the fabric of the trouser and preclude edgewise movement of the plate with respect to such fabric.

5. A wear guard for trousers comprising a shell-like wear plate provided along one of its edges and on the back side thereof with a walled passage of oval cross section extending parallel to the edge of the plate, a wire extending through said passage and projecting beyond the opposite ends thereof, the projecting parts of said wire being bent into parallel relation and sharpened at their free ends, those portions of the wire within the opposite ends of the passage being in alignment with one another and the intermediate portion of said wire being offset in the plane of the prongs, and spurs formed on the plate and projecting in a backward direction to impale the fabric of a trouser when the prongs are impaled in said fabric and the wear plate folded down to bring the spurs into engagement with the fabric.
